TIRE CHAINING TOOL

John R. Hutton, 837 Morning Glory St.,
West Sacramento, Calif. 95691

Filed Oct. 24, 1974, Ser. No. 517,479

Term of patent 14 years

Int. Cl. D8—05

U.S. Cl. D8—31

FIG. 1 is a front elevational view of a tire chaining tool showing my new design, with the adjacent portion of a conventional side chain fastener shown in broken line for the sole purpose of illustrating the environment in which the tool is used;

FIG. 2 is an elevational view of one side thereof;

FIG. 3 is an elevational view of the other side;

FIG. 4 is a rear elevational view;

FIG. 5 is a front end view; and

FIG. 6 is a rear end view thereof.

I claim:

The ornamental design for a tire chaining tool, as shown and described.
